(57) **CLAIM**

The ornamental design for a obtuse angle range adjustable square assembly, as shown and described.

DESCRIPTION

FIG. 1 is a front view of the obtuse angle range adjustable square assembly.

FIG. 2 is a back view of the obtuse angle range adjustable square assembly.

FIG. 3 is a top view of the obtuse angle range adjustable square assembly relative to the square position shown in FIG. 1.

FIG. 4 is a bottom view of the obtuse angle range adjustable square assembly relative to the square position shown in FIG. 1.

FIG. 5 is a left side view of the obtuse angle range adjustable square assembly relative to the square position shown in FIG. 1.

FIG. 6 is a right side view of the obtuse angle range adjustable square assembly relative to the square position shown in FIG. 1; and,

FIG. 7 is a front view of the obtuse angle range adjustable square assembly showing the parts.
